(57) **CLAIM**

The ornamental design for a fetch toy substantially as shown and described.

DESCRIPTION

FIG. 1 is a top, front, left, 3D perspective view of the fetch toy.

FIG. 2 is a top, rear, right, 3D perspective view thereof.

FIG. 3 is a front elevation view thereof.

FIG. 4 is a rear plan view thereof.

FIG. 5 is a right side view thereof.

FIG. 6 is a left side view thereof.

FIG. 7 is a top plan view thereof.

FIG. 8 is a bottom plan view thereof.

FIG. 9 is a top, front, left, 3D perspective view of a second embodiment of the fetch toy.

FIG. 10 is a top, rear, right, 3D perspective view thereof.

FIG. 11 is a front elevation view thereof.

FIG. 12 is a rear plan view thereof.

FIG. 13 is a right side view thereof.

FIG. 14 is a left side view thereof.

FIG. 15 is a top plan view thereof.

FIG. 16 is a bottom plan view thereof.

FIG. 17 is a top, front, left, 3D perspective view of a third embodiment of the fetch toy.

FIG. 18 is a top, rear, right, 3D perspective view thereof.

FIG. 19 is a front elevation view thereof.

FIG. 20 is a rear plan view thereof.

FIG. 21 is a right side view thereof.

FIG. 22 is a left side view thereof.

FIG. 23 is a top plan view thereof; and,

FIG. 24 is a bottom plan view thereof.

(Continued)

The broken lines illustrate portions of the fetch toy that form no part of the claimed design.
